DESIGN FOR A DRESS

Elizabeth Noble, New York, N. Y.

Application September 10, 1937, Serial No. 71,530

Term of patent 3½ years

To all whom it may concern:

Be it known that I, Elizabeth Noble, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the specific lace embroidery on the waist and sleeve portion of the dress as shown in combination with the spangles along the edge of the lace as shown.

I claim:

The ornamental design for a dress, substantially as shown and described.

ELIZABETH NOBLE.
